(57) CLAIM

The ornamental design for an angel figurine, as shown and described.

DESCRIPTION

FIG. 1 is a perspective view of the angel figurine, showing the new design;

FIG. 2 is a front view of the angel figurine thereof;

FIG. 3 is a rear view of the angel figurine thereof;

FIG. 4 is a left view of the angel figurine thereof;

FIG. 5 is a right view of the angel figurine thereof;

FIG. 6 is a top view of the angel figurine thereof; and,

FIG. 7 is a bottom view of the angel figurine thereof.

The broken lines in FIG. 7 in the drawings represent portions of the angel figurine and form no part of the claimed design.
